UNITED STATES PATENT OFFICE

2,277,422

ELECTRIC CIRCUIT BREAKER

Ludwig S. Walle, Lansdowne, Pa., assignor to
General Electric Company, a corporation of
New York

Application March 8, 1940, Serial No. 322,908

10 Claims. (Cl. 200—151)

My invention relates to electric circuit breakers and more particularly to arc-extinguishing devices for circuit breakers of high interrupting capacity.

Within comparatively recent times and concomitant with various developments and improvements of apparatus of this general character, there has been an increasing tendency to employ air circuit breakers or the like instead of oil circuit breakers in the construction of electrical generating stations, substations and associated equipment for the generation and distribution of electric power. This is based largely on the desire to eliminate oil from electrical equipment insofar as possible so as to reduce the fire hazard and danger of explosions to a minimum.

Many circuit breakers have been proposed which eliminate the fire hazard due to oil by employing a fluid blast, such as air or other gas, for example, for arc-extinguishing purposes. As a general rule, these circuit breakers require a source of fluid pressure and associated control apparatus which greatly increases the expense and complication of the apparatus. It would be desirable to have an electric circuit breaker which eliminates the fire hazard associated with oil circuit breakers and yet wherein no complicated means need be provided for producing a source of fluid under pressure which may be utilized for arc-extinguishing purposes.

Accordingly, it is an object of my invention to provide a new and improved electric circuit breaker of high interrupting capacity which is simple and compact, utilizes a minimum number of moving parts, and which is relatively inexpensive to manufacture.

It is another object of my invention to provide an improved circuit interrupter capable of interrupting large amounts of power with a shorter arcing time than has been heretofore considered necessary without the requirement of complicated associated apparatus for arc-extinguishing purposes.

It is a further object of my invention to provide an electric circuit breaker wherein one of the relatively movable contacts is completely enclosed upon separation of said contacts in a chamber formed of a gas-evolving insulating material so as to be isolated from the other contact thereby to insure shorter arcing time, less danger of restriking and therefore higher interrupting capacity.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying draw-

ing in which Fig. 1 is an elevational view in cross section of an electric circuit breaker embodying my invention, and Fig. 2 is a sectional view taken on line 2—2 of Fig. 1.

5 Referring now to the drawing and more particularly to Fig. 1, I have illustrated a circuit breaker embodying my invention contained in a suitable insulating casing 10. This casing or housing may be constructed of any desirable insulating material and may even comprise laminated wood or the like. Casing 10 is provided with an insulating liner 11 which is made of a material from which gas is evolved under the influence of the heat of the arc drawn in the circuit breaker, which, at least in part, aids in extinguishing the arc. This liner may comprise inorganic materials, such as boric acid, ammonium alum, or organic materials, such as horn fibre and the like, or material formed of methyl methacrylate, as described and claimed in United States Letters Patent No. 2,157,815, granted May 9, 1939, upon an application of Ralph V. Boyer, and assigned to the same assignee as the present invention.

20 The relatively movable contacts of the circuit breaker illustrated in Fig. 1 comprise a pair of stationary electrodes or contacts 12 and 13 suitably fastened to a pair of terminal members 14 and 15, respectively, which are fixedly mounted 30 to insulating housing 10 by any suitable means 16, and a movable horizontally positioned rod contact member or electrode 17 adapted to cooperate with fixed contacts 12 and 13, thereby providing two series breaks in the electric circuit when the circuit breaker is opened. Stationary contacts 12 and 13 are provided with contact tips 12' and 13', respectively, formed of an arc-resisting metal while movable rod contact member 17 is provided with contact tips 17a and 17b also formed of a suitable arc-resisting metal. The contact tips 12' and 13' of the respective fixed contacts 12 and 13 are provided with slightly inclined surfaces which cooperate with somewhat similar surfaces on contact tips 17a and 17b of contact member 17 to insure good electrical contact when the circuit breaker is closed. If desired any suitable well known wiping means may be provided.

25 In order to produce relative movement between movable horizontally positioned contact rod 17 including contact tips 17a and 17b and fixed contacts 12 and 13, I provide a barrier 20 of insulating material vertically reciprocal in casing 10 in a pair of slides formed by suitable 35 guide bars 21 fastened to the interior of housing 10. Barrier 20 is adapted to pass through openings 22 and 23 in housing 10 and may be connected by means 24 to any suitable operating mechanism, not shown, which may, for example, 40 comprise a suitable solenoid or spring-operating

mechanism, or any other arrangement well known in the art.

Rod contact member 17 is suitably mounted in fixed relationship with vertically reciprocating barrier 20 by being supported in an insulating tube 25 which passes through an opening formed in barrier 20 and is suitably attached to the latter. Upward movement of barrier 20 will cause a separation of rod contact 17 and associated fixed contacts 12 and 13 to interrupt the electric circuit associated with terminals 14 and 15 of the circuit breaker while closing of the circuit breaker is accompanied by downward movement of barrier 20.

In order to obtain high interrupting capacity of the circuit breaker as well as a compact design, I provide cylindrical envelopes or bushings 26a and 26b slidably mounted over the respective ends of rod contact member 17 protruding from barrier 20. These sleeves or bushings 26a and 26b are formed of a suitable gas-evolving material similar to that from which liner 11 is formed. Sleeves or bushings 26a and 26b are shorter than the associated portion of contact member 17 protruding from barrier 20 and are provided with spring members 27a and 27b, respectively, suitably mounted in a countersunk portion in bushings 26a and 26b for biasing said bushings away from barrier 20 so as to tend to enclose rod contact member 17 more completely. The lower edges of sleeves 26a and 26b remote from barrier 20 are arranged in the downward movement thereof to engage with inclined surfaces 18' and 19' of protrusions 18 and 19 respectively which may be integral with insulating liner 11 so as to allow the contacting surfaces 17a and 17b of horizontally positioned rod contact member 17 to extend beyond the ends of sleeve bushings 26a and 26b and protrusions 18 and 19 hold bushings 26a and 26b in this retracted position when the circuit breaker is in the closed position illustrated in Fig. 1 so that electrical contact between arcing tips 17a, 17b and 12', 13' respectively, may be made. When barrier 20 is moved upwardly by suitable means, not shown, to interrupt the electric circuit associated with terminals 14 and 15 of the circuit breaker, spring means 27a and 27b force sleeves or bushings 26a and 26b, respectively, away from barrier 20 and against the liner 11 of gas-evolving insulating material. When this occurs, contact 17 is completely enclosed in chambers formed by bushings 26a and 26b and liner 11 so as to be isolated from fixed contacts 12 and 13. The arcs drawn upon interruption of the circuit are snuffed out when the ends of bushings 26a and 26b rub along insulating liner 11 and high-speed interruption is obtained. The open condition of the circuit breaker is illustrated by the position of contact member 17 and associated bushings 26, shown dotted in Fig. 1.

In order that the arc gases and arc products formed during the interruption of the circuit may escape from casing or housing 10, suitable exhaust ports 28 and 29, respectively, are provided in housing 10 adjacent fixed contacts 12 and 13.

The operation of the circuit breaker will be obvious to those skilled in the art in view of the detailed description included above. However, when the circuit breaker is in the position illustrated in Fig. 1, protrusions 18 and 19 of liner 11 hold bushings 26a and 26b against the tensions of their respective associated springs 27a and 27b, whereby contacting surfaces 17a

and 17b of rod contact 17 may engage with the arcing tips 12' and 13', respectively, of fixed contacts 12 and 13. Interruption of the circuit is obtained by moving barrier 20 upwardly, carrying movable rod contact 17 along therewith, whereupon the electric circuit is broken and an arc is drawn between arcing tips 12' and 17a and 13' and 17b, respectively. Further upward movement of barrier 20 will allow bushings 26a and 26b to move away from barrier 20 toward insulating liner 11. The heat of the arc will cause gases to be evolved both from liner 11 and from bushings 26a and 26b which will aid in the extinguishment of the arcs. Slidable movement of bushings or sleeves 26a and 26b will continue until the bushings are free from fixed contacts 12 and 13, whereupon these bushings will rub against liners 11 snuffing out the arc and completely enclosing fixed contact member 17 in a cylindrical chamber formed of an insulating material emitting an arc-extinguishing gas. The open position of the circuit breaker is indicated in dotted lines in Fig. 1 and, in view of the fact that contact member 17 is completely surrounded by insulating material in this position, the separation of the contacts for isolating purposes need not be so great to prevent restriking of the arc as in prior art arrangements wherein one of the contacts is not completely isolated from the other. This makes for a more compact arrangement. The arc gases formed during the circuit interruption process are allowed to escape through exhaust ports 28 and 29.

While I have shown a particular embodiment of my invention as applied to electric circuit breakers, it will be apparent to those skilled in the art that my invention is not limited to the construction shown but that changes and modifications may be made without departing from the spirit and scope of my invention and I aim in the appended claims to cover all such changes and modifications.

What I claim as new and desire to secure by Letters Patent of the United States, is:

1. In an electric circuit breaker, the combination comprising a casing, a plurality of relatively movable contacts supported within said casing, means for producing relative movement between said contacts to make or break the electric circuit associated with said circuit breaker, a sleeve-like bushing of gas-evolving insulating material movably positioned on one of said contacts and arranged so as to allow said one contact to protrude therefrom to engage another of said contacts during the closed circuit position of said circuit breaker, and means for causing effective withdrawal of said one contact into said sleeve-like bushing upon separation of said relatively movable contacts and for causing said bushing to engage said casing so that high-speed interruption of said circuit may be obtained.

2. In an electric circuit breaker including a casing, the combination of a pair of relatively movable contacts associated with said casing, means for producing relative movement between said contacts to interrupt the current in an associated electric circuit, a sleeve of gas-evolving insulating material movably positioned on one of said contacts and biased so as to tend to extend beyond the end of said one contact, means for moving said insulating sleeve so that said one contact protrudes therefrom to engage with said other contact during the closed circuit position of said circuit breaker, and means for allowing said biasing means to become effective upon separation of said contacts.

ration of said relatively movable contacts to cause said sleeve to engage said casing so as to isolate completely said one contact whereby high-speed interruption of said circuit may be obtained.

3. In an electric circuit breaker, the combination comprising a pair of relatively movable contacts, means for producing relative movement between said contacts to interrupt the current in an associated electric circuit, an insulating sleeve movably positioned on one of said contacts, a surface for limiting the movement of said sleeve by engaging with the end thereof adjacent the contacting portion of said one contact, said insulating sleeve being arranged so that said one contact may protrude therefrom to engage said other contact during the closed circuit position of said circuit breaker, and means for causing said insulating sleeve to engage said surface for snuffing out the arc drawn upon separation of said relatively movable contacts.

4. In an electric circuit breaker, the combination comprising a pair of relatively movable contacts, a casing for said contacts, means for producing relative movement between said contacts to interrupt the current in an associated electric circuit, an insulating sleeve movably positioned on one of said contacts, a liner for said casing arranged to engage the end of said sleeve adjacent the contacting portion of said one contact when said first-mentioned means are operative, said insulating sleeve being arranged to allow said one contact to protrude therefrom to engage said other contact during the closed circuit position of said circuit breaker, and means for causing said insulating sleeve to engage said liner for snuffing out the arc drawn upon separation of said relatively movable contacts.

5. In an electric circuit breaker, the combination of a casing, a pair of relatively movable contacts mounted within said casing, means for producing relative movement between said contacts to interrupt the current in an associated electric circuit, an insulating bushing movably positioned on one of said contacts, the end of which is adapted to be moved against one of the walls of said casing to define a chamber within said bushing, said bushing being positioned so that said contact protrudes therefrom in the closed circuit position of said circuit breaker, and means for causing said contact to be enclosed completely in said chamber upon separation of said relatively movable contacts whereby interruption of said circuit is insured.

6. In an electric circuit breaker, the combination comprising a casing, a pair of relatively movable contacts supported within said casing, means for producing relative movement between said contacts to make or break the electric circuit associated with said circuit breaker, a sheath of gas-evolving insulating material movably positioned on one of said contacts, a liner of gas-evolving insulating material for said casing for limiting the movement of said sheath by engaging with the end thereof adjacent the contacting portion of said one contact, said sheath being arranged so that said one contact may protrude therefrom to engage said other contact during the closed circuit position of said circuit breaker, and means for causing said sheath to engage said liner upon separation of said relatively movable contacts whereby said arc is rapidly extin-

guished by the combined snuffing action of said sheath and liner and the arc-extinguishing gas evolved therefrom.

7. In an electric circuit breaker, the combination comprising a casing, a pair of relatively movable contacts supported within said casing, means for producing relative movement between said contacts to make or break the electric circuit associated with said circuit breaker, an envelope of gas-evolving insulating material movably positioned on one of said contacts, a liner of gas-evolving insulating material for said casing for limiting the movement of said envelope by engaging with the end thereof adjacent the contacting portion of said one contact, said envelope being arranged so that said one contact may protrude therefrom to engage said other contact during the closed circuit position of said circuit breaker, and spring means for biasing said envelope so as to engage said liner upon separation of said relatively movable contacts, whereby the arc drawn by such separation causes gas to be evolved which together with the snuffing action of said envelope and liner rapidly extinguishes said arc.

8. In an electric circuit breaker, the combination comprising a pair of relatively movable contacts, a casing for said contacts, means for producing relative movement between said contacts to interrupt the current in an associated electric circuit, an insulating sleeve movably positioned on one of said contacts, and insulating means associated with said casing for causing movement of said insulating sleeve upon engagement with said last-mentioned means so as to allow said contact to protrude therefrom to engage said other contact during the closed circuit position of said circuit breaker.

9. In an electric circuit breaker, the combination comprising a pair of relatively movable contacts, a casing for said contacts, means for producing relative movement between said contacts to interrupt the current in an associated electric circuit, an insulating sleeve movably positioned on one of said contacts and arranged to engage said casing to limit movement in one direction thereof, said insulating sleeve being arranged so that said one contact may protrude therefrom to engage said other contact during the closed circuit position of said circuit breaker, means for causing said insulating sleeve to engage said casing for snuffing out the arc drawn upon separation of said relatively movable contacts, and exhaust ports in said casing whereby the arc products during such circuit interruption may escape.

10. In an electric circuit-interrupting device including a casing, the combination comprising a pair of arcing electrodes associated with said casing, a member of gas-evolving insulating material surrounding one of said electrodes and adapted to engage said casing, said member being movable relatively to said one electrode under certain operating conditions of said circuit-interrupting device, and means tending to cause said member to engage said casing to enclose said one electrode completely so that high-speed interruption of an arc between said electrodes may be obtained.
